United States Patent Office

Des. 218,851
Patented Sept. 29, 1970

218,851

PROBE COVER

Stephens N. Sato, San Diego, Calif., assignor to Ivac Corporation, San Diego, Calif., a corporation of California

Filed Aug. 4, 1969, Ser. No. 18,535

Term of patent 14 years

Int. Cl. D10—09

U.S. Cl. D52—7

FIG. 1 is a perspective view of a probe cover embodying my new design;

FIG. 2 is a longitudinal view, the view being the same in both plan and elevation, of the probe cover shown in FIG. 1;

FIG. 3 is a left end elevational view of the probe cover shown in FIG. 2;

FIG. 4 is a right end elevational view of the probe cover shown in FIG. 2;

FIG. 5 is a perspective view of another embodiment of a probe cover embodying my new design;

FIG. 6 is a longitudinal view, the view being the same in both plan and elevation, of the probe cover shown in FIG. 5;

FIG. 7 is a left end elevational view of the probe cover shown in FIG. 6; and

FIG. 8 is a right end elevational view of the probe cover shown in FIG. 6.

I claim:
The ornamental design for a probe cover, as shown.
